WARNER T. TABB, OF MAHWAH, NEW JERSEY

HAIR CURLER.

Application filed October 23, 1924. Serial No. 745,316

This invention relates to improvement in hair curlers and has for one of its objects to provide an improved curler capable of being conveniently adjusted in its operative position and thereafter heated to produce an effective curl.

Another object is to securely attach the body of the curler to the hair by means of cooperating clamping devices and to insert into said body a heating element, the heat from which is conveyed to the hair through a portion of said body.

A further object is to so construct the body of the curler and the heating element that the latter may be easily and quickly attached to the body and securely maintained in its operative position without disturbing the curl which is formed upon the body.

A still further object is to provide a
20 curler of sufficiently light weight and having
in itself a sufficient means of insulating
the heat of the above mentioned element
from the head of the user, that the body of
25 the curler may be conveniently and com-
fortably left in position as long as desired,
after the hair has been wound and clamped
thereon and the hot element inserted therein.

Still another object is to provide a curler which will effectively enclose the hair wound on the body thereof.

The above and other objects will appear more clearly from the following detailed description, when taken in connection with the accompanying drawings, which illustrate preferred embodiments of the inventive idea.

In the drawings

Figure 1 is a perspective view of one form of the invention;

Figure 2 is a vertical longitudinal section therethrough taken on the line 2—2 of Figure 3;

Figure 3 is a section on the line 3—3 of Figure 2;

Figure 4 is a fragmentary end elevation, 45 partly broken away and shown in section;

Figure 5 is a view of the curler showing the parts detached one from the other;

Figure 6 is an elevation showing the manner of handling the heating element when being mounted in the body of the curler;

Figure 7 is a side elevation, partly broken away and shown in section, of another form of the invention;

Figure 8 is a section on the line 8—8 of Figure 7;

Figure 9 is an elevational view showing a different means for maintaining the heating element or cartridge in position in the curler;

Figure 10 is a fragmentary view, partly broken away and shown in section, in which the retaining means of Figure 9 is employed for mounting the heating element or cartridge in the body of the curler; 60

Figure 11 is a fragmentary longitudinal section of another implement which may be employed to turn the curler to wind the hair thereon and to support the heating element while the latter is being inserted into the curler: 70

Figure 12 is a side elevation showing the manner of supporting the heating element with the implement shown in Figure 11; and

Figure 13 is a side elevation showing the manner of supporting the curler on the implement while winding the hair on the curler. 75

Referring particularly to the form of the invention shown in Figures 1 to 6 inclusive, the curler is illustrated as comprising a body including a cylindrical spindle 14, preferably made of a light material such as aluminum having a relatively high specific heat. Each end of the spindle is formed with a circumferential groove 15 for receiving the inner periphery of an end plate or disk 16, also made of a light material, but preferably one having a relatively low specific heat and a low heat conductivity. The extremities of the spindle are flared or crimped, as indicated at 17, to engage the outer surfaces of

the end plates so as to retain said plates in position on the spindle. The outer peripheries of the end plates may be covered with annular rings 18 employed to protect the head of the user against engagement with

the sharp edges of the end plates. The body thus resembles a flanged spool in construction and the end plates provide a means for confining the hair to be curled upon the 100

spindle and the edges of said plates will space the spindle from the head of the user and thus effectively protect the user against the heat of the spindle. By making the end

the heat of the spindle. By making the plates as thin as possible and of a material such as spring steel having a low specific heat and a low heat conductivity, it will be apparent that the heat from the spindle will not be readily transmitted through said plates. To still further limit the transmis- 110

sion of heat through the end plates some of the material of the plates may be removed as by means of the holes 38 shown in Figure 8, which are equally spaced in the mid periphery of the end plates 16.

In curling short or bobbed hair the free ends of the hair are first laid upon the spindle 14 and then partially secured in position by means of an inner clamping device 19 of 10 substantially three-quarter cylindrical formation, as shown in Figure 3. A sufficient amount of the hair is then wound about the spindle and clamping device 19 to form a curl whereupon an outer clamping device 20, also of three-quarter cylindrical formation, is engaged over the wound portion of the hair to enclose the same between said clamping devices and retain the hair in its wound or curled condition. The clamping devices 19 and 20 are made of suitable resilient material so that when slightly expanded and mounted in operative position the hair will be frictionally gripped thereby aiding in its retention in a curled condition. 20 The free longitudinal edges of the clamping devices 20 are turned outwardly, as indicated at 21, to facilitate the handling of the clamping device. By arranging the clamping devices, as shown in Figure 3, with the 30 spaces between the free longitudinal edges of said devices oppositely disposed with respect to their positions about the spindle, it will be apparent that the hair to be curled is practically entirely enclosed between said 35 clamping devices and that the latter will effectively retain heat from the spindle to secure a maximum application of said heat to the hair to be curled.

After the hair has thus been wound upon 40 the spindle and secured in position, a heating element or cartridge 22, which has been previously heated, is mounted within the cylindrical spindle, as shown in Figure 2. The heating element 22 will preferably be 45 made of some light material such as aluminum having a high specific heat so that for a given weight of material and a given temperature of the heating element the largest possible amount of heat will be retained 50 thereby and will so be available for heating the hair. Each end of the heating element is preferably provided with a longitudinally extending recess 23 capable of receiving the free ends of a supporting device 24. This 55 device may be formed of a single length of material, such as wire, bent intermediate the ends thereof to form a handle and having its extremities arranged adjacent each other so that by slight compression of the handle portion said extremities may be brought together and inserted in one of the recesses 23. The opposite end of the heating element is then inserted into one end of the spindle 14 and said heating element moved 60 to a position wherein the ends thereof are

confined within said spindle. In order to retain the heating element in position within the spindle a resilient retaining device 25 is provided. This device is preferably made of a single length of wire having its extremities 26 bent in opposite directions and engaged in openings 27 in the end plates and interposed between said plates and the spindle, as best shown in Figure 4. Intermediate the ends of the device 25 the same 70 is bent to form a loop 28 which projects through an opening 29 formed in the spindle 14. At a point intermediate the ends of the heating element the same is provided with an annular groove 30 into which the loop 80 28 projects when the heating element is in proper position within the spindle and this loop 28 will then releasably maintain the heating element in said spindle. After the heating element is mounted in position the 85 heat therefrom will be conducted to the hair through the spindle and clamping device 19. The curler may be removed by simply detaching the clamping device 20, after which the hair may be unwound from the 90 spindle and by finally removing the clamping device 19 the hair is completely detached from said spindle.

This invention may also be used for curling long hair, in which case the hair is 95 wound upon the spindle 14 from the inner ends of the hair outwardly. In this event, the inner clamping device 19 is dispensed with, but the outer clamping device 20 may be employed as before to retain the hair 100 in position on the spindle.

Figures 7 and 8 show a form of this invention in which the resilient retaining device 25 is omitted. The spindle in this case is made of relatively thin material so as to 105 have in itself considerable resiliency. The end plates 16 are secured to the spindle in substantially the same manner as previously described. However, the spindle, as shown in Figure 7, is split longitudinally as indicated at 31 and provided upon one edge of said split and intermediate the ends of the spindle with an instruck projection or tongue 32 which is designed to engage the groove 30 of the heating element when the 110 same is introduced into the spindle.

In the drawings there is shown the end disks 16 constructed as separate parts and attached to the spindle 14. These disks may, however, be constructed as part of the 115 spindle by using for the spindle a suitable material such as steel and flaring its ends to form the disks as flanges.

A holding and retaining device 33 made of a single length of wire may be employed 120 in mounting the heating element 22 in the spindle and retaining the same in operative position. This device 33 may be formed of a single length of wire bent intermediate its 125 ends to form a looped handle 34 and having 130

its extremities projecting inwardly toward each other, as clearly shown in Figures 9 and 10. To mount the heating element in the spindle one extremity of the device 33 may be engaged with the element 22, as illustrated in Figure 10, and the other end of the element then inserted into the spindle. After the element is in position in the spindle both of the extremities of the device 33 may be engaged in the openings in the ends of said element, as shown in Figure 9, and in this manner the heating element will be prevented from becoming accidentally detached from the body of the curler.

15 In Figure 11 an implement is shown, the shank of which includes two cooperating gripping members 36 both of arcuate formation in cross section. The members 36 are formed of resilient material and are shaped 20 to fit closely into the spindle. Previous to the positioning of the heating element within the spindle the implement 35 may be employed, as illustrated in Figure 13, to form a handle for the curler when winding the 25 hair thereon. When so used the free extremities of the members 36 are inserted into the spindle and due to the resilient nature of said members the same will frictionally grip the spindle so that the handle of the 30 implement 35 may be employed to turn the curler and thus wind the hair on the spindle thereof.

This implement may also be utilized in handling the heating element 22, particularly in removing the element from the flame or pan in which it has been heated. For this purpose the ends of the members 36 are provided with internal notches 37 of a 40 cylindrical shape, adapted to engage the heating element as shown in Figure 12.

What is claimed is:

1. In a hair curler, a body including a hollow spindle, a clamping device independent of the spindle to retain ends of hair in engagement with said spindle, a second clamping device independent of said spindle engageable with hair wound upon said spindle to retain the wound hair in curled condition, and a heatable cartridge insertable 50 into said spindle after the hair is wound thereon.

2. In a hair curler, a body on which to wind the hair, said body including a central portion and end plates attached to said central portion, said plates being made of material having, relative to said central portion, a low specific heat and a low heat conductivity; a heating element insertable in

said body, and means to retain said heating element in operative position.

3. In a hair curler having a hollow spindle, a heatable cartridge insertable into said spindle, an instrument attachable to said spindle and independently attachable to said cartridge, said instrument having a 60 body and cooperating resilient members axially extending in the same direction therefrom but oppositely disposed about the axis thereof, said members acting to frictionally engage the inner surface of said spindle when inserted therein, said members having at their free ends transverse notches to engage the outer surface of said cartridge when said cartridge is inserted between said members transversely thereof.

4. In a hair curler, a spindle on which to wind the hair; said spindle having flanges adjacent the ends thereof, and rims for said flanges, said rims constituting longitudinal enlargements of said flanges adjacent 70 the peripheries of the same.

5. In a hair curler, a body including a hollow spindle upon which the hair to be curled is wound, a heating element insertable into said spindle, and end plates for 80 said spindle capable of retaining the hair thereon and spacing the spindle from the head of the user.

6. In a hair curler comprising a hollow body on which to wind the hair and a heatable cartridge insertable into said body and a recess in said cartridge; a detachable automatically expanding handle for said cartridge, said handle comprising a pair of elongated end portions thereof manually movable to positions adjacent each other for insertion into said recess, and a resilient portion of said handle acting to separate said end portions to bring said end portions in engagement with the peripheral surface 95 of said recess when said end portions are inserted therein.

7. In a hair curler comprising a hollow body on which to wind the hair, a heatable cartridge insertable into said body, said cartridge having a substantially cylindrical shape and a longitudinally extending recess in said cartridge, said recess being substantially cylindrical in shape and open at an end of said cartridge to receive a suitable 105 tool to grip said cartridge internal of said recess for handling said cartridge while hot.

In testimony whereof I have affixed my signature.

WARNER T. TABB.
